UNITED STATES PATENT OFFICE.

EISABURO SAKASAI, OF TOKYO, JAPAN.

FOUNTAIN PEN.

Application filed July 20, 1922. Serial No. 576,340.

To all whom it may concern:

Be it known that I, EISABURO SAKASAI, a subject of the Emperor of Japan, residing at No. 13, Itchome, Matsui-cho, Honjo-ku, Tokyo, Japan, have invented certain new and useful Improvements in Fountain Pens, of which the following is a specification.

This invention relates to improvements in fountain-pens of the type comprising a rubber tube or reservoir provided within a barrel and secured at one end to the rear end of a pen section.

In the fountain-pens of this type, it is already known, that, in order to press or collapse the rubber reservoir, a pressure bar is arranged parallel therewith, and a lever is projectingly provided at the central portion of the said bar, a slide being so pivoted to the said lever that it may be moved along the outside periphery of the barrel, with the effect that the lever will be raised or lowered for causing the pressure bar to move in the direction vertically of the moving direction of the slide.

In the previous fountain-pens, however, the vertical movement of the lever is hard to be effected on account of incomplete connection means for the slide and the lever, and further, as the pivotal points of the said two elements come to the dead points of crank motion of the lever, the operation of the slide is very difficult, and besides these, there are many disadvantages and defects such as, for example, the pressure bar may be easily flexed with the result of putting the pen out of use quite soon.

The object of this invention is to provide a fountain-pen without such defects, which comprises, for the connection of the lever and the slide, a pair of fixing members adapted to support the barrel and the slide by being secured to the latter at the outer end and bent down at the other on to the inner wall of the former. The pivot pin for the said fixing members and the lever is made with different diameters, the middle portion of which is larger than both end portions, and the length of the said middle portion of a large diameter is somewhat longer than the width of the lever so that the same may be properly operated in vertical direction without being pressed by the fixing members. The pressure bar is made of a thin metal strip with a comparatively large width, and is turned up or doubled at

both sides. The curved parts of the said bar are further straightened upwardly so as to form projecting edges, which serve to stiffen the thin metal plate and prevent the same from flexing. The projecting edges are made sloped or inclined so that the lever may be operated easily without producing the dead point of crank motion when the lever is pressed down.

The constructions, operations and advantages of the parts of the fountain-pen in accordance with this invention will be fully described hereinafter, with reference to the accompanying drawings, in which:

Figure 1 is a longitudinal sectional view of the fountain-pen, according to this invention, showing as when the rubber tube or reservoir is collapsed or pressed down,

Figure 2 is a similar view to Figure 1, but, showing as when the said reservoir is held in normal or released position,

Figure 3 is a cross sectional view taken on line 3—3 of Figure 1,

Figure 4 is also a cross sectional view taken on line 4—4 of Figure 2,

Figure 5 is a diagrammatical perspective view of the principal parts of this invention, i. e., the slide, lever, pressure bar, pins and a pair of fixing members,

Figure 6 is a fragmentary view of the pressure bar, showing also the lever pivoted thereto,

Figure 7 is an enlarged view of a part of Figure 3, and

Figure 8 is a reference view drawn for better understanding of this invention.

In the accompanying drawings, 1 is a barrel with open and closed ends. The open end is freely engaged with the pen section 2 which carries a pen 3 at its top end and has a stepped portion 4 at the other. Within the barrel 1, there is provided a rubber tube or reservoir 5, and, one end of which is engaged with the stepped portion 4 of the pen section and the other is free and closed. The said reservoir is normally kept expanded by the elasticity of itself, as shown in Figure 2, and is adapted to reserve the ink and further to supply the pen with it through the feeding groove 6 in the same manner as in the ordinary pens. 7 is the pressure bar which is provided along one side of the rubber reservoir 5 within the barrel 1, and is adapted for eliminating the air or ink from the said reservoir by means of collapsing the same,

as shown in Figure 5. As in Figure 5, the said pressure bar is a strip of metal plate and is formed with a double or turned up portion 7^a along each side. The edges of the 5 said doubled portions are further turned upwardly so as to form projecting edges 7^b which serve to give inflexible nature to the bar 7 of a flexible metal strip. 8 are a pair of protrusions upheaving from the middle 10 portion of the said projecting edges, and are provided with a pin hole 9. 10 is a lever having pin holes 10^a and 10^b at the upper and lower ends respectively, and is pivoted, between the protrusions 8, to the upper central 15 parts of the pressure bar 7 by means of the pivot pin 11 passing through holes 9 and 10^b. 12 is a guide hole formed in the intermediate wall of the barrel 1. 13 is a slide made of thin metal plate which is fixed to 20 the outer side of the said guide hole so as to be adapted for sliding along the outer periphery of the barrel 1, and has a pair of fixing holes 13^a formed in the center and as well as a variety of suitable designs and the 25 like worked on its surface. 14 are a pair of fixing members of thin metal plate, each of which is adapted to connect the slide 13 with the top end of the lever 10, and is provided with a projection 14^a at the top end and also 30 a pin hole directly below the said projection, as shown in Figure 5. The said fixing members 14 are secured to the slide 13 by bending or curving the upper parts of the 35 projections 14^a down on to the surface of the slide 13, after passing the said projections through the fixing holes 13^a of the slide 13. The lower part 14^c of each fixing member is curved outwardly so as to fit closely with the inner surface of the wall of the barrel 40 1, and by the cooperation of this curved portion 14^c and the bent end of the projection 14^a the slide 13 and the wall of the barrel are supported together so that the former 45 may rest upon the latter. Consequently the slide 13 may travel quite steadily and smoothly along the guide hole 12 without any involuntary slipping. 15 is a pivot pin, the middle portion of which is of a suitable 50 diameter for fitting with the pin hole 10^a and the both ends is of a suitable diameter for fitting with the hole 14^b of the fixing members 14. The said middle thick portion of the pivot pin 15 has a slightly longer 55 length than the width of the lever 10, and the said pivot pin connects the slide 14 pivotally with the lever 10 by running through the pin holes 10^a and 14^b. The reason for forming the pivot pin 15 into two portions of different diameters will be described here- 60 under. If the diameter of the said pin were same throughout, as in Figure 8, the middle parts of the fixing members being apt to swell in the direction indicated by an arrow 65 when the same are bent at their upper projections 14^a and lower parts 14^c, they would

so strongly press the lever lying therebetween that the latter would receive inconvenience of no small measure in the swinging movement on account of the friction of the said lever with the fixing members, and consequently, the sliding movement of the slide 13 would be checked. And further, if the pressure given by the fixing members were lightened or reduced for the purpose of avoiding such a disadvantage as above, the 75 slide would have the disposition to move involuntarily and there would be a constant danger that the said slide would move without being operated by hand, causing the ink in the reservoir to be pushed out. In brief, with the pivot pin of the same diameter, as shown in Figure 8, the suitable moderate connection between the pin and the fixing members can be hardly obtained. When the pivot pin 15 is formed into two parts of 80 different diameters, as shown in Figures 7, the lever 10 will never be pressed strongly between the fixing members for the reason that the latter being stopped at the stepped portion of the pin 15, even though the upper and lower ends of the fixing members are bent as strongly as possible to the slide and the wall of the barrel; therefore, the friction between the above two members can be avoided, and the slide may always be fitted 85 closely with the barrel, thus eliminating the danger of the involuntary slipping of the slide. 90

The projecting edges 7^b of the pressure bar 7 are slightly sloped, that is, they are 100 made thicker or higher gradually in the forward direction wherein the lever 10 lies. The reason for providing the projecting edges 7^b with such slope or inclination is as follows (see Figure 6): The slide 13 being 105 arranged to be operated in the direction parallel with the base of the pressure bar 7, it will be clearly seen that the dead point of crank motion of the lever 10 in respect to the pivot pin 11 lies on the parallel line 7^a—7^a 110 with the base 7^c—7^c involving the said pin 11; consequently, when the lever 10 is rested down in parallel with the base 7^c—7^c, the slide may not be moved, for the reason that, in this case, the pivot pin 15 of the lever 10 115 is placed at the dead point of crank motion with reference to the pivot pin 11. While, in case the projecting edges 7^b are given slope, the pin 15 of the lever 10 is always retained out of the parallel line 7^a—7^a, so also is the dead point, and therefore the slide 13 may be moved smoothly to cause the lever to move in a vertical direction. 120

Briefly, the advantageous feature of the fountain-pen, according to this invention, 125 relates to the mechanism transmitting the movement of the slide 13 to the pressure bar 7, that is, the lever 10, fixing members 14 and pivot pin 15, etc., and with this feature many disadvantages and defects heredi- 130

tary to the fountain-pens of this type are overcome, and the practical effect is obtained.

I claim:—

5. 1. A fountain-pen comprising a pen section, a rubber tube or reservoir provided within a barrel and secured at one end to the rear end of the said pen section, a pressure bar provided in parallel with the said reservoir, a lever projectingly arranged at the middle portion of the said bar and a slide connected to the said lever, the said rubber reservoir being adapted to be collapsed by the said pressure bar in accordance with the sliding movement of the said slide; characterized by this that the lever being connected with the slide by means of a pair of fixing members secured at the top end to the slide and bent down on to the 20 inner wall of the said barrel at the lower end so as to be adapted to support the slide and the barrel wall with the said two curved ends, in order to move the slide steadily along the barrel without any involuntary slipping.
2. A fountain-pen according to claim 1, characterized by this that the lever and the fixing members are connected together by means of a pivot pin which is formed with 25 a large diameter in its middle portion and with a small diameter at both ends, the length of the said middle portion of a large diameter being made longer than the width of the lever so as to reduce the friction between the said fixing members and the lever.

3. A fountain-pen, according to claim 1, characterized by this that the pivot pin at the top end of the lever is arranged to re-

main permanently out of the dead point of crank motion in respect to the lower pivot pin, when the lever is pressed down.

4. A fountain-pen, according to claim 1, characterized by this that the pressure bar is provided at one side with an inclined member.

5. In a fountain pen structure, a hollow barrel, a collapsible ink reservoir located in said barrel, a pressure member engaged with the reservoir having longitudinal ribs forming a channel therein, a member slidably mounted on the barrel and a link connection between the slideable member and said pressure member and received within the channel in the latter.

6. In a fountain pen structure, a hollow barrel having a slot therein, a collapsible ink reservoir located within the barrel, a pressure member engaged with said reservoir, a member slidably mounted on said barrel and a link connection between said slideable member and said pressure member, said slideable member including a plate overlying said slot, and a pair of fixing members secured to said plate, extending through said slot and pivotally connected with said link, 65 said fixing members having the inner extremities thereof engaged with the interior of the barrel on opposite sides of the slot for guiding the movement of the plate and preventing displacement of the latter from 70 the barrel.

In testimony whereof I affix my signature.

EISABURO SAKASAI.
